UNITED STATES PATENT OFFICE.

ALFRED H. HUMPHREY AND GEORGE A. HUMPHREY, OF NEW YORK, N. Y.

GAS-BURNER.

1,388,433.

Specification of Letters Patent. Patented Aug. 23, 1921.

Application filed August 3, 1920. Serial No. 400,895.

To all whom it may concern:

Be it known that we, ALFRED H. HUMPHREY and GEORGE A. HUMPHREY, citizens of the United States, residing at the city and county of New York, State of New York, have invented certain new and useful Improvements in Gas-Burners, of which the following is a specification.

This invention relates to improvements in 10 gas burners.

The main objects of this invention are:

First, to provide an improved gas burner of very high efficiency.

Second, to provide an improved gas 15 burner in which the heat units are very effectively directed to an article being heated, such as a cooking utensil.

Third, to provide an improved gas burner in which both the direct heat of the flame 20 and the radiant heat are utilized.

Further objects, and objects relating to structural details will definitely appear from the detailed description to follow.

We accomplish the objects of our invention 25 by the devices and means described in the following specification. The invention is clearly defined and pointed out in the claims.

A structure which is a preferred embodiment of our invention is clearly illustrated 30 in the accompanying drawing, forming a part of this specification, in which:

Fig. I is a plan view of a structure of the gas plate type embodying the features of 35 our invention, the gas supply pipe and valve and supports being broken away.

Fig. II is a detail view partially in vertical section on a line corresponding to line 2-2 of Fig. I, a cooking utensil being shown 40 arranged upon the top or grid.

Fig. III is a detail view partially in section corresponding to Fig. II of a modified form of our invention, the modification being in the baffle member and its supports.

Fig. IV is a plan view of the baffle member of Fig. III.

Fig. V is a plan view of another modification or embodiment of our invention in which the baffle members are omitted.

Fig. VI is a detail view partially in section on a line corresponding to line 6-6 of Fig. V, a cooking utensil being shown on the grid or top.

Fig. VII is a detail view partially in vertical section of another modification in

which our improvements are adapted to a burner of the annular type.

In the drawing similar reference characters refer to similar parts throughout the several views, and the sectional views are 60 taken looking in the direction of the little arrows at the ends of the section lines.

Referring to the drawing, 1 represents a frame of a gas stove or gas plate of the well-known type, a single burner being illustrated. The stove is provided with a top or grid 2 adapted to support the object to be heated such as a vessel 3 shown conventionally in Figs. II and VI. The burner embodying the preferred form of our invention 70 is shown in Figs. I and VI and comprises a body or head 4 having a bunsen 5 receiving the gas from the nozzles 6, see Fig. V. The delivery of the gas from the supply pipe 7 is controlled by the valve 8. As the 75 arrangement of the valve and the bunsen are well understood, we do not describe them with further detail herein.

The burner is provided with a plurality of tips 9. These are preferably of the structure shown in Letters Patent, No. 1,245,346, issued November 6, 1917, to the applicant, Alfred H. Humphrey, such burners being especially desirable for use with our improvements. The burner tips 9 are disposed 80 through openings 10 in the pan or bowl-shaped deflector member 11 which constitutes a combustion chamber for the burner and a deflector and guard whereby the burner is protected from air currents and 85 the heat is directed upwardly through the grid, not only the direct heat of the flame but also the radiant heat. The deflector member is disposed with its upper edge adjacent to but spaced from the under edge of 90 the grid.

This fire back or deflector member 11 is formed of an earthy or fire clay composition adapted to become incandescent when heated, and is of substantial body. The deflector 100 member is preferably provided with an outer metal shell 12 which is well protected from the heat, and may be enameled or otherwise finished. The burner tip openings 10 are of such dimensions as to provide for 105 the passage of secondary air to the burner tips. The tips are disposed so that the flames issue at the bottom of the deflector.

The deflector member is preferably provided with internal projections 13, those in 110

the structure illustrated being in the form of radially disposed fins formed integrally with the deflector member.

To protect the burner tips and also to increase the radiant heat quality of the burner, we mount baffle plates 14 above the burner tips. These are preferably mounted on posts 15 formed integrally with the deflector member and grouped about the openings 10 supporting the plates as illustrated. These baffle members must be formed of some material which will withstand intense heat, nichrome being very satisfactory.

In the modification shown in Figs. III and VI the baffle member 16 is formed of a plate having solid baffle portions 17 located above the burner surrounded by perforations 18 for the passage of the products of combustion. In the modification shown in Figs. V and VI, the baffle members are omitted entirely. This embodiment is very satisfactory although it is an advantage to protect the burner tips from liquids and the like which may fall upon the burner as the result of boiling over or the spilling of the liquids thereon.

In the modification shown in Fig. VII, the annular burner 19 provided with a plurality of jet orifices 20 is arranged within the deflector member 21. In this embodiment the deflector member has holes 22 in the bottom thereof for the passage of the secondary air. The internal projections are omitted in this embodiment.

In the embodiments shown in the other figures, in addition to the flange-like projections on the side portions of the deflector, we preferably provide the bottom with a series of conical projections 23. These internal projections materially increase the radiating surface of the deflector. In use, the deflector constitutes a combustion chamber for the burner, protecting it from air currents which would deflect or carry away the heat, further, it becomes heated to incandescence in use as do also the baffle members so that a large amount of radiant heat is directed upwardly through the grid.

We find that our improved burner has the further advantage of consuming a very high percentage of the combustible portions of the gas, and is of exceedingly high efficiency.

We have not illustrated or described certain adaptations and embodiments of our invention which we contemplate as being desirable in applying our improvements in other relations as we believe the disclosure made will enable those skilled in the art to which our invention relates to embody or adapt the same as may be desired.

Having thus described our invention, what we claim as new and desire to secure by Letters Patent is:

1. The combination with a grid, of a gas burner having a plurality of upwardly pro-

jecting burner tips, a pan-shaped deflector member disposed with its upper edge adjacent the under side of said grid and having openings in its bottom through which said burner tips project, there being spaces around said tips for the passage of secondary air thereto, said deflector member being of earthy material and having integral radially disposed internal fins and an integral baffle plate supporting posts disposed about the burner tip openings thereof, baffle plates disposed on said posts above said burner tips, and an outer metal shell for said deflector member.

2. The combination with a grid, of a gas burner having a plurality of upwardly projecting burner tips, a pan-shaped deflector member disposed with its upper edge adjacent the under side of said grid and having openings in its bottom through which said burner tips project, there being spaces around said burner tips for the passage of secondary air thereto, said deflector member being of earthy material, and an outer metal shell for said deflector member.

3. The combination with a grid, of a gas burner having a plurality of upwardly projecting burner tips, a pan-shaped deflector member through which said tips are disposed, said deflector member being of fire resistant material adapted to become incandescent when heated and integral baffle plate supporting posts, and baffle plates disposed on said posts above said burner tips.

4. The combination with a grid, of a gas burner having a plurality of upwardly projecting burner tips, and a pan-shaped deflector member through which said tips are disposed, said deflector member being of fire resistant material adapted to become incandescent when heated and having integral internal projections.

5. The combination of a burner and a deflector member therefor open at the top and having a secondary air opening at the bottom, disposed to constitute a combustion chamber for said burner, said deflector member being of earthy material and provided with integral radially disposed internal fins and integral baffle plate supporting posts, and a baffle plate arranged on said posts above the burner tips.

6. The combination of a gas burner and pan-shaped deflector member disposed to constitute a combustion chamber for the burner, said deflector member being of fire resistant material adapted to become incandescent when heated and being provided with internal integral fins.

7. The combination with a grid, of an upwardly flaring pan-shaped deflector member disposed below said grid with its upper edge adjacent to but spaced therefrom, said deflector member having burner tip openings in its bottom and being of fire resistant ma-

- terial adapted to become incandescent when heated, and a gas burner disposed below said deflector member and having a plurality of tips projecting upwardly through said openings in said deflector member with the ends of the tips substantially flush with the bottom thereof, there being a space around said tips for the passage of the secondary air.
8. The combination with a grid, of an upwardly flaring pan-shaped deflector member disposed below said grid with its upper edge adjacent to but spaced therefrom, said deflector member being of fire resistant material adapted to become incandescent when heated, and a gas burner disposed below said deflector member and having a plurality of tips projecting upwardly through the bottom of said deflector member with the ends of the tips substantially flush therewith.
- 10 9. The combination with a grid, of a gas burner, an upwardly flaring pan-shaped deflector member of fire resistant material adapted to become incandescent when heated, disposed with its upper edge adjacent to but spaced from said grid, said burner being disposed so that the deflector member constitutes a combustion chamber and so that the flames are delivered at the bottom thereof, and a baffle plate disposed above the burner.
- 15 10. The combination with a grid, of a gas burner, an upwardly flaring pan-shaped deflector member of fire resistant material adapted to become incandescent when heated, disposed with its upper edge adjacent to but spaced from said grid, said burner being disposed so that the deflector member constitutes a combustion chamber and so that the flames are delivered at the bottom thereof.
- 20 11. The combination with a grid, of a gas burner, an upwardly flaring pan-shaped deflector member of fire resistant material adapted to become incandescent when heated, disposed with its upper edge adjacent to but spaced from said grid, said burner being disposed so that the deflector member constitutes a combustion chamber and so that the flames are delivered at the bottom thereof.

In witness whereof we have hereunto set our hands and seals in the presence of two witnesses.
